UNITED STATES PATENT OFFICE.

JEAN B. TAUVERON, OF NEW YORK, N. Y.

BOTTLE.

SPECIFICATION forming part of Letters Patent No. 660,404, dated October 23, 1900.

Application filed January 19, 1900. Serial No. 2,066. (No model.)

To all whom it may concern:

Be it known that I, JEAN BAPTISTE TAUVERON, a citizen of France, and a resident of the city of New York, (Bath Beach,) borough of Brooklyn, in the county of Kings and State of New York, have invented a new and Improved Bottle, of which the following is a full, clear, and exact description.

This invention relates to improvements in bottles of the non-refillable class, and for which I have received Letters Patent of France under date of June 20, 1899, No. 290,123.

The object of the invention is to provide a bottle of this class that shall be comparatively cheap to manufacture and so arranged that refilling will be practically impossible, thus preventing fraudulent use of the bottle.

I will describe a bottle embodying my invention and then point out the novel features in the appended claims.

Reference is to be had to the accompanying drawings, forming a part of this specification, in which similar characters of reference indicate corresponding parts in all the figures.

Figure 1 is a sectional elevation showing a bottle embodying my invention. Fig. 2 is a section on the line 2 2 of Fig. 1. Fig. 3 is a side view of a mouthpiece employed. Fig. 4 is a section on the line 4 4 of Fig. 3. Fig. 5 is a sectional elevation showing a modification. Fig. 6 is a section on the line 6 6 of Fig. 5. Fig. 7 is a side view of a mouthpiece used in this modification, and Fig. 8 is a section on the line 8 8 of Fig. 7.

Referring to Fig. 1 of the drawings, 1 designates the neck portion of a bottle, the lower portion of which has an interior annular shoulder 2, forming a seat for the float-valve 3. Above the valve-seat portions of the neck are pressed inward to form guide-ribs 4 for the valve, the space between these ribs serving as ports for the passage of liquid when the bottle is tilted and the valve moved slightly out of its seat. Arranged in the neck of the bottle and serving as a weight to keep the valve normally in its seat is a ball 5, of glass or other suitable material.

Arranged in the upper portion of the bottle-neck is a mouthpiece 6, of suitable material—such, for instance, as glass. The upper portion of this mouthpiece is tubular and

the lower end is in the form of a block 7. Between the block 7 and the tubular portion of the mouthpiece longitudinally-inclined ports 8 are formed. The lower ends of these ports 8 register with channels 9 on the periphery of the block 7, these channels being inclined reversely to the incline of the ports. By this construction it will be rendered impossible to insert a wire or similar instrument to engage with the valve to raise it from its seat. The upper portion of the mouthpiece 6 is provided at its outer side with an annular channel 10, designed to register with an annular channel 11, formed in the interior of the bottle-neck, and below the channel 10 of the mouthpiece an annular shoulder 12 is formed. The flange connecting the shoulder 12 with the channel 10 is provided with a series of openings or notches 13, through which cement may pass.

In use after filling the bottle the valve and weight are to be placed in the neck thereof. Then, after placing a cement in a semiliquid or soft state around the upper portion of the mouthpiece and then a washer 14, of cork or similar material, the mouthpiece is to be forced into the bottle-neck. While forcing the mouthpiece into the bottle-neck the cement will be forced upward through the notches 13, filling the channels 10 and 11 and also filling the space between the shoulder 12 and the washer 14, while said washer is resting on an annular shoulder 15, formed in the bottle-neck. Surplus cement passing upward above the end of the bottle-neck may be scraped off, and when the cement becomes hardened the mouthpiece cannot be removed.

To discharge liquid from the bottle, it is to be tilted so that the weight 5 will roll against the lower end of the block 7, permitting the valve 3 to escape from its seat. Then the liquid will pass through the ports between the ribs 4, through the channels 9, ports 8, and the tubular portion of the mouthpiece. Before or after placing the mouthpiece in the bottle-neck a cork may be placed in the mouthpiece, as indicated in Fig. 1.

In Fig. 5 I have shown the improvement as adapted to a bottle having a straight or ordinary neck 16. In this device I employ a valve-casing 17, having an opening through its bottom, and a valve-seat 18 for the float-

valve 3, which is engaged by the weight 5, as before described. Above the valve-seat the casing is provided with guide-ribs 18^a, serving the purpose of the ribs 4, as before described. At its upper end the valve-casing has an outwardly-extended flange 19, which engages above an interior annular shoulder 20, formed in the bottle-neck. The mouthpiece 6 has the ports 8 and the channels 9 arranged in a similar manner to the example first described; but in this instance the lower end or block 21 is made in the form of an inverted cup to receive the weight 5, as plainly shown in the drawings. The mouthpiece 6 is provided with the annular channel 10, registering with the channel 12^a in the bottle-neck, to receive cement, and the operation of inserting this modification of the device is the same as first described.

Having thus described my invention, I claim as new and desire to secure by Letters Patent—

1. In a bottle, a mouthpiece arranged in the bottle-neck and having at its upper portion an annular channel for registering with a channel formed in the bottle-neck for re-

ceiving cement, an annular channel below the channel of the mouthpiece and communicating therewith through notches through which cement may pass, a block at the lower end of the mouthpiece and having inclined channels communicating with oppositely-inclined ports between the block and upper portion of the mouthpiece, and a valve in the neck below the mouthpiece, substantially as specified.

2. In a bottle, a tubular mouthpiece having inclined ports registering with oppositely-inclined channels in the periphery of a block at the lower end of and integral with the mouthpiece, a valve-casing into which the lower portion of the mouthpiece extends, a valve in said casing, and a weight for the valve, substantially as specified.

In testimony whereof I have signed my name to this specification in the presence of two subscribing witnesses,

JEAN B. TAUVERON.
